UNITED STATES PATENT OFFICE.

WILLIAM H. NICHOLLS, OF BROOKLYN, NEW YORK.

MOLDING MACHINE.

Application filed June 24, 1924. Serial No. 722,103.

This invention relates to improvements in that type of machine shown in Patents No. 1,277,745, dated September 3, 1918 and 1,472,807 dated November 6, 1923.

- 5 In a molding machine embodying this invention and constructed as illustrated and described herein, the sand may be mechanically jolted to tightly pack it in a flask around a pattern, the flask and the pattern 10 being so supported that after the jolting operation they may be rolled over and the mold then squeezed. After the squeezing operation the pattern is supported above the flask and the flask may then be lowered to 15 withdraw the pattern. As the flask is lowered it is automatically lifted from the jolting and squeezing means by a conveyor, so that it may be readily rolled along the conveyor out of the machine.
- 20 It is necessary that the pattern be at the bottom of the flask during the jolting operation in order that the sand may be firmly packed about it. In the two patents hereinbefore mentioned the patterns are drawn 25 down from the flask. This, in many instances, requires that the mold shall be turned over by hand after the patterns have been withdrawn and after the mold has been removed from the machine. With some 30 forms of patterns this turning over of the mold after the pattern has been withdrawn is dangerous to the mold, that is to say, it is apt to result in the breaking down of the parts of the mold. This is particularly so 35 in the large patterns and heavy molds. It is desirable therefore to provide a simple and efficient means by which the mold may be rolled over after the jolting operation and before the squeezing operation so that it may 40 be squeezed in a position reverse to the position it was in during the jolting operation. It is also desirable to provide means whereby after the squeezing operation the flask may be lowered and the pattern plate supported 45 in its elevated position. This results in the mold being completed and in position to be taken out of the machine right side up for the pouring operation. By rolling over the mold in the machine and before the squeezing 50 operation all danger of injury to the mold is avoided.

It is also desirable, and particularly in making heavy molds, to provide means for automatically lifting the mold from the jolting and squeezing means and permitting it

to be moved out of the machine without bodily and manually lifting it from the squeezing mechanism. This also avoids injury to the molds and increases the speed of operation and reduces the amount of manual labor necessary in the operation.

I wish it understood that I am not to be limited to the construction of machine illustrated herein for the reason that the invention is capable of many modifications and 65 may be applied to machines differing materially in construction from the machine illustrated in the drawings and described herein.

In the drawings, Fig. 1 is a side elevation partly in section of a molding machine constructed in accordance with this invention;

Fig. 2 a front elevation partly in section taken on the line 2—2 of Fig. 1;

Fig. 3 a plan view of the machine;

Fig. 4 a sectional view on the line 4—4 75 of Fig. 3;

Fig. 5 a detail perspective view of one of the conveyor bars;

Fig. 6 a side elevation partly in section of the rotatable pattern holding head;

Fig. 7 a plan view of the pattern holding head;

Fig. 8 an end elevation of the pattern holding head;

Fig. 9 a front elevation showing the mold 85 in transverse section with the pattern holding head rolled over and in position for the squeezing operation;

Fig. 10 a view similar to Fig. 9 illustrating the squeezing operation; and

Fig. 11 a view similar to Figs. 9 and 10 90 illustrating the pattern withdrawing operation.

Referring to the various parts by numerals, 1 designates the base of the machine, 95 said base being provided with oppositely extending rigid arms or brackets 2 and 3. The base is formed with a central vertical cylinder 4 which is open at its upper end and closed at its lower end by a horizontal wall 5. In the arm 2 is rigidly mounted an upstanding post 6 on the upper end of which is rotatably mounted a horizontally swinging frame arm 7. The frame arm 7 carries the upper pressure head 8 which is connected to said arm by screw 9 threaded through a suitable bushing mounted in the arm. The pressure head is so positioned on the arm that it may be brought directly over the center of the cylinder 4 for the squeezing 100 105 110

operation, as will be hereinafter described. In the free end of the frame arm is formed a vertically disposed jaw 10 which is adapted to engage and to receive the upper end of a rigid upstanding rod 11 which is rigidly mounted at its lower end in the frame arm 3. When the jaw 10 is in engagement with the rod 11 the pressure head 8 is directly over the center of the cylinder 4. The pressure head 8 carries on its lower face a magnetic head 12 which may be connected to a suitable source of electric current by means of the connection plug 13. The magnetic head 12 forms the lower face of the pressure head 8 and may be magnetized by closing a switch in the electric circuit, the switch being conveniently located for manipulation by the operator. The upper end of the rod 11 is provided with a collar in the form of an adjustable nut which is adapted to engage the upper end of the jaw 10 and to take the up-thrust on the pressure head during the squeezing operation. The arm 7 carrying the pressure head may be readily swung rearwardly away from the molding machine whenever desired, as illustrated in Fig. 3.

In the cylinder 4 is fitted a large squeeze-piston 14 which is closed at its lower end and open at its upper end. The upward movement of the squeeze-piston is limited by the headed bolts 15 which are rigidly mounted in the bottom wall 5 of the cylinder and extend upwardly through apertures in the bottom wall of the piston, as shown clearly in Fig. 1. A small vertically arranged cylinder 16 is formed at the center of the squeeze-piston, the upper end of this cylinder being open and the lower end thereof being formed by the bottom wall of the squeeze-piston. A short distance above the bottom of this cylinder 16 is formed an exhaust port 17 which places the said small cylinder in communication with the interior of the larger portion of the squeeze-piston and thence to atmosphere. Mounted in the smaller cylinder 16 is a hollow jolt piston 18. This piston is open at its lower end and is provided with a cross wall 19 a short distance upwardly from its lower end. Extending through this cross wall is an air supply pipe 20 which leads out through the upper end of said piston to an air control valve 21 mounted on the rigid arm 3 of the base. An air supply pipe 22 leads from the valve 21 through the bottom wall 5 to supply air under the squeeze-piston 14. The control valve 21 is of the usual, or of any suitable, construction and is adapted to be operated by the handle 23. Formed integrally with the upper end of the jolt piston is a jolt and squeeze head 24. The lower end of this head is adapted to rest on the upper end of the squeeze-piston, as shown clearly in Fig. 1.

A vertically arranged air cylinder 25 is rigidly connected to the rigid bracket 2. As shown in Fig. 2 this cylinder is formed integrally with the bracket, but of course it may be secured thereto in any suitable manner. This cylinder is arranged close to the vertical post 6 and is parallel therewith. In the cylinder 25 is arranged a piston 26 carrying an upwardly extending piston rod 27 which projects through the cap closing the upper end of the said cylinder. Slidably mounted on the post 6 is a long sleeve 28 which is provided at its lower end with a laterally extending foot 29. The upper end of the piston rod 27 is rigidly connected to the foot 29 so that the sleeve 28 will be moved up and down on the post 6 in response to the movements of the piston 26. The sleeve 28, when in its lowermost position, rests on the upper surface of the bracket 2, 85 said bracket forming a rigid stop and rest for the sleeve. In the lowermost position of the sleeve 28 the piston 26 is at the bottom of the cylinder. An air valve 30 is connected by a pipe 31 to the bottom of the cylinder 25 so that by properly manipulating the valve air will be admitted under the piston 26. This valve may be of any suitable construction and it is thought unnecessary to illustrate it in detail. The valve is adapted to be operated by means of the handle 32. Mounted on the sleeve 28 is a vertically movable and horizontally rotatable support 33. This support is adapted to engage a shoulder 34 formed near the bottom of the sleeve 28. When the sleeve 28 is moved upwardly the shoulder 34 will engage the lower end of the support 33 and carry said support upwardly with it. Formed on one side of the support 33 is a tapered tubular bearing 35, the axial center of said bearing being horizontal. In this tubular bearing is mounted a horizontal journal 36 of a pattern holding head 37. The pattern holding head is substantially rectangular in form and is provided at its outer side, that is to say the side nearest the vertical post 6, with a large circular vertically arranged flange 38. The journal 36 extends outwardly from the center of this flange, and it is tapered to fit within the tapered bearing 35. Suitable ball bearings support the journal. The pattern holding head 37 is connected to the flange 38 near the lower margin thereof, the upper horizontal pattern holding surface 39 being considerably below the axial center of the flange 38 and the journal 36. The flange 38, at diametrically opposite points in a horizontal plane, is provided with two latch receiving sockets 40. The bearing 35 is formed with a horizontal tubular extension 41 adapted to receive a spring pressed latch bolt 42, the spring tending to force the latch inwardly into engagement with sockets 40. The outer end of the latch bolt 42 is con-

nected to a horizontally swinging lever 43 pivoted to the bearing 35. The latch bolt serves to lock the pattern supporting head in horizontal position, as will be hereinafter described. The pattern plate 44 is rigidly secured to the surface 39 of the pattern supporting head by screws or other suitable fastening means, passing through the pattern plate and into threaded sockets 45 in the pattern holding head. The pattern plate is provided with the usual laterally extending lugs 46 carrying upstanding centering pins 47 which are adapted to pass through apertured lugs formed on the flask to properly center the flask with respect to the pattern plate. The pattern supporting head may be swung horizontally on the post 6 to move it away from the jolting and squeezing mechanism, as shown in Fig. 3. This head is also rotatable on the horizontal journal 36 for the purpose of inverting the pattern holding head; and the latch bolt 42 is adapted to lock the pattern holding head in horizontal position either above or below the horizontal axis of the journal 36. When the pattern holding head is in its normal lower position it is adapted to rest directly on the jolting and squeezing piston head 24. In this position of the pattern holding head the lower end of the support 33 is a short distance above the shoulder 34 of the sleeve 28 so that in the jolting operation the said support will not engage the shoulder 34. As shown in the drawings the pattern holding head is formed with a flat bottom to engage the magnetic head when the mold is rolled over, but of course it may be of any suitable form. The flask 48 is formed with perforated lugs 49 adapted to fit down over the centering pins 47 carried by the pattern plate to center the flask over the pattern.

The base of the machine, at diametrically opposite points, is formed with two vertically arranged sockets 50, said sockets extending the entire depth of the base. Rigidly secured to the jolting and squeezing piston head 24 are two depending guide plungers 51 which are fitted snugly in the sockets 50 to accurately guide the head 24 in its up and down movement. Secured rigidly to the upper surface of the base of the machine are two rails 52, said rails extending fore and aft of the machine, one on each side of the head 24. Each rail is formed with upstanding lugs in which are journalled rollers 53, said rollers being on the inner side of the rails, that is to say on the sides nearer the center of the head 24. The rollers are so arranged that the forward ones are slightly higher than the rear ones, all of said rollers comprising a roller conveyor which inclines slightly rearwardly and downwardly. The rollers are so located that their upper margins are above the upper surface of the

head 24, but are below the pattern receiving surface 39 when the pattern supporting head is resting on the jolting and squeezing head 24. At the rear of the machine is preferably arranged a roller conveyor 54 onto which the molds may be moved from the rollers 53, as will be hereinafter described.

The operation of the machine may be briefly described as follows:

The flask is placed in position on the pattern plate and the pattern plate holding head is brought to rest on the head 24. The flask is then filled with sand and the valve operated to admit air through the pipe 20 for the purpose of vibrating the jolting piston 16 and the connected head 24. During this jolting operation the pattern supporting head is vibrated, the support 33 moving up and down on the sleeve 28. After the jolting operation the flask is filled smoothly with sand and the presser board 55 placed in position in the flask, as shown in Fig. 1. The presser board is temporarily clamped in position by means of the clamps 56 which engage the edges of the presser board and the edges of the pattern plate. The presser board is considerably wider than the flask for a purpose which will be hereinafter described. After the presser board has been secured in position the valve 30 is operated to admit air below the piston 26 to thereby elevate the sleeve 28 on the post 6. As the sleeve 28 moves upwardly the shoulder 34 picks up the support 33 and thereafter the pattern holding head and the flask move upwardly with the sleeve 28. When the flask has been sufficiently elevated the entire flask support may be swung around laterally on the post 6, if desired, or if the flask is not too high it may be allowed to remain in position directly over the jolting and squeezing mechanism. When the pattern supporting head is in the desired elevated position the latch bolt 42 is released from the flange of the pattern supporting head whereupon the said head and the flask will roll over, that is to say will reverse their positions. This roll over operation will be practically automatic because the greater portion of the weight of the flask will be above the horizontal axial line of the journal 36 so that it will be necessary for the operator merely to upset the balance of the flask after the latch 42 has been released. The latch 42 will then engage the other socket in the flange 38 and thereby lock the pattern holding head in its rolled over position and maintain it horizontal. When the flask and the pattern holding head have been thus rolled over and locked more air is admitted into the cylinder 25 to complete the upward movement of the piston 26 and the sleeve 28. A collar 57 is rigidly secured to the post 6 to limit the upward movement of the sleeve 28. When the sleeve 28 has engaged the collar 57 the

pattern holding head is slightly below the magnetic face 12 of the upper pressure head 8. This is for the purpose of preventing the pattern holding head being forced against the magnetic head through the operation of the lifting piston 26. When the sleeve 28 has reached the limit of its upward movement air pressure is maintained in the cylinder 25 to hold the flask and the pattern holding head in their elevated positions. The valve 21 is now operated to admit air below the squeeze piston, thereby forcing upwardly the jolt and squeeze head 24 and bringing said head into engagement with the presser board 55, as shown in Fig. 10. The upward movement of the squeeze piston causes the support 33 to move upwardly on the sleeve 28 and brings the pattern supporting head into direct engagement with the magnetic head 12. The operator then closes the switch to complete the electric circuit through the magnetic head thereby magnetically clamping the pattern holding head to the upper presser head. The pattern holding head is, of course, made of suitable metal so that it will be securely magnetically clamped and supported. It is, of course obvious that when the pressing operation begins the temporary clamps 56 will drop away from the presser board and the pattern plate.

After the roll over operation the pattern plate and the pattern holding head are reversed with respect to their positions during the jolting operation and the flask is in position to be lowered away from the pattern plate. To draw the flask downwardly away from the pattern the valve 21 is operated to release air from below the squeeze piston 14. This permits the flask and the completed mold to draw away from the pattern, the pattern holding head and the pattern being held in their elevated positions by the magnetic head. As the squeeze piston and the jolting and squeezing head 24 approach the limit of their downward movement the presser board 55 comes into contact with the rollers 53 so that the flask with the presser board therein is deposited on the inclined conveyor, the head 24 moving down below said rollers and leaving the mold on the rollers. As the series of rollers incline slightly toward the rear of the machine the mold may be readily moved rearwardly from the machine and on to the conveyor 54.

After the drawing operation is complete the current is cut off from the magnetic head and the pattern supporting head will drop until the lower edge of the support 33 engages the shoulder 34 of the sleeve 28. The valve 30 may then be operated to exhaust air from the cylinder 25 to thereby permit the sleeve 28 and the pattern holding head to recede. As the head is moving

downwardly the latch bolt 42 is released from the flange 38 and the pattern holding head will then automatically roll over to its normal position. When it has reached its lower horizontal position the latch bolt 42 again engages one of the sockets in flange 38 and locks the holding head in position to receive another flask. The pattern holding head will automatically roll over upon the release of the latch 42 because the weight thereof is above the horizontal axial line of the journal 36.

The upper pressure head 8 and the arm 7 may be swung laterally out of the way of the flask during the roll over operation or during the operation of moving the completed mold from the machine. It will, of course, be swung back into locked position before the squeezing operation. The pattern holding head may be swung laterally at any time for the convenient manipulation of the machine. It may be swung laterally for convenience in placing a flask thereon or for the roll over operation.

What I claim is:

1. In a molding machine the combination of a support, a large squeeze piston mounted in said support, a smaller jolt piston mounted centrally in the squeeze piston, a valve for controlling a supply of fluid under pressure to said pistons, a head carried by the upper end of the jolt piston and adapted to bear on the upper end of the squeeze piston, a pattern plate holding head adapted to rest on the head of the jolt piston, vertically movable means for supporting the pattern plate holding head independently of the jolting and squeezing pistons, means rotatably supporting the pattern plate holding head to permit it to be rotated about a horizontal axis to invert said head, means for raising the pattern plate holding head independently of the jolting and squeezing pistons, and means for holding the pattern plate holding head in elevated position after it has been inverted by rotating it on its horizontal axis.

2. In a molding machine the combination of a support, a mold squeezing means carried by said support, a pattern plate holding head adapted to rest on the mold squeezing means, vertically movable means for supporting the pattern plate holding head independently of the squeezing means, means rotatably supporting the pattern plate holding head to permit it to be rotated about a horizontal axis to invert said head, means for raising the pattern plate holding head independently of the squeezing means, and means for holding the pattern plate holding head in elevated position after it has been inverted by rotating it on its horizontal axis.

3. In a molding machine the combination of a support, a mold jolting and squeezing means carried by said support, a pattern

- plate holding head adapted to rest on the mold jolting and squeezing means, vertically movable means for supporting the pattern plate holding head independently of the 5 squeezing means, means rotatably supporting the pattern plate holding head to permit it to be rotated about a horizontal axis to invert said head, means for raising the pattern plate holding head independently of the 10 jolting and squeezing means, and means for holding the pattern plate holding head in elevated position after it has been inverted by rotating it on its horizontal axis.
4. In a molding machine the combination 15 of a support, a large squeeze piston mounted in said support, a smaller jolt piston mounted centrally in the squeeze piston, a valve for controlling a supply of fluid under pressure to said pistons, a head carried by the 20 upper end of the jolt piston and adapted to bear on the upper end of the squeeze piston, a pattern plate holding head adapted to rest on the head of the jolt piston, vertically movable means for supporting the pattern 25 plate holding head independently of the jolting and squeezing pistons, means rotatably supporting the pattern plate holding head to permit it to be rotated about a horizontal axis to invert said head, means for 30 raising the pattern plate holding head independently of the jolting and squeezing pistons, and magnetic means for holding the pattern plate holding head in elevated position after it has been inverted by rotating 35 it on its horizontal axis.
5. In a molding machine the combination 40 of a support, a mold squeezing means carried by said support, a pattern plate holding head adapted to rest on the mold squeezing means, vertically movable means for supporting the pattern plate holding head independently of the squeezing means, means rotatably supporting the pattern plate holding head to 45 permit it to be rotated about a horizontal axis to invert said head, means for raising the pattern plate holding head independently of the squeezing means, and magnetic means for holding the pattern plate holding head in elevated position after it has been inverted 50 by rotating it on its horizontal axis.
6. In a molding machine the combination 55 of a support, a mold jolting and squeezing means carried by said support, a pattern plate holding head adapted to rest on the mold jolting and squeezing means, vertically movable means for supporting the pattern plate holding head independently of the squeezing means, means rotatably supporting the pattern plate holding head to 60 permit it to be rotated about a horizontal axis to invert said head, means for raising the pattern plate holding head independently of the jolting and squeezing means, and magnetic means for holding the pattern plate holding head in elevated position after it has been 65
- inverted by rotating it on its horizontal axis.
7. In a molding machine the combination 70 of a support, a mold squeezing means carried by said support, a pattern plate holding head adapted to rest on the mold squeezing means, vertically movable means for supporting the pattern plate holding head independently of the squeezing means, means rotatably supporting the pattern plate holding head to permit it to be rotated about a 75 horizontal axis to invert said head, means for raising the pattern plate holding head independently of the squeezing means, an upper pressure head adapted to be engaged by the pattern plate holding head after the 80 said head has been inverted, and means for holding the pattern plate holding head in engagement with said upper pressure head independently of the mold squeezing means.
8. In a molding machine the combination 85 of a support, a mold squeezing means carried by said support, a pattern plate holding head adapted to rest on the mold squeezing means, vertically movable means for supporting the pattern plate holding head independently of the squeezing means, means rotatably supporting the pattern plate holding head to permit it to be rotated about a horizontal axis to invert said head, means for raising the pattern plate holding head independently of the squeezing means, an upper pressure head adapted to be engaged by the pattern plate holding head after the 90 said head has been inverted, and magnetic means for holding the pattern plate holding head in engagement with said upper pressure head independently of the mold squeezing means.
9. In a molding machine the combination 95 of a base, a mold squeezing means carried by said base, a pattern plate holding head adapted to rest on the mold squeezing means, vertically movable means for supporting the pattern plate holding head independently of the squeezing means, means rotatably supporting the pattern plate holding head to 100 permit it to be rotated about a vertical axis to move said head away from the squeezing means, and means rotatably supporting the pattern plate holding head to permit it to be rotated about a horizontal axis to invert said head.
10. In a molding machine the combination 105 of a base, a mold squeezing means carried by said base, a pattern plate holding head adapted to rest on the mold squeezing means, vertically movable means for supporting the pattern plate holding head independently of the squeezing means, means rotatably supporting the pattern plate holding head to 110 permit it to be rotated about a vertical axis to move said head away from the squeezing means, and means rotatably supporting the pattern plate holding head to permit it to be rotated about a horizontal axis to invert said head.
11. In a molding machine the combination 115 of a base, a mold squeezing means carried by said base, a pattern plate holding head adapted to rest on the mold squeezing means, vertically movable means for supporting the pattern plate holding head independently of the squeezing means, means rotatably supporting the pattern plate holding head to 120 permit it to be rotated about a vertical axis to move said head away from the squeezing means, means rotatably supporting the pattern plate holding head to permit it to be rotated about a horizontal axis to invert said head, and an upper pres-

sure head adapted to be engaged by the inverted pattern plate holding head during the mold squeezing operation.

11. In a molding machine the combination of a base, a mold squeezing means carried by said base, a pattern plate holding head adapted to rest on the mold squeeze means, vertically movable means for supporting the pattern plate holding head independently of the squeezing means, means rotatably supporting the pattern plate holding head to permit it to be rotated about a horizontal axis to invert said head, and an upper pressure head adapted to be engaged by the inverted pattern plate holding head during the mold squeezing operation.

12. In a molding machine the combination of a support, a mold squeezing means carried by said support, a pattern plate holding head adapted to rest on the mold squeezing means, vertically movable means for supporting the pattern plate holding head independently of the squeezing means, means rotatably supporting the pattern plate holding head to permit it to be rotated about a horizontal axis to invert said head, pneumatic means for raising the pattern plate holding head independently of the squeezing means, and means for holding the pattern plate holding head in elevated position after it has been inverted.

13. In a molding machine the combination of a base, a mold squeezing means carried by said base, a pattern plate holding head adapted to rest on the mold squeeze means, vertically movable means for supporting the pattern plate holding head independently of the squeezing means, means rotatably supporting the pattern plate holding head to permit it to be rotated about a horizontal axis to invert said head, pneumatic means for raising the pattern plate holding head independently of the squeezing means, and an upper pressure head adapted to be engaged by the inverted pattern plate holding head during the mold squeezing operation.

14. In a molding machine, the combination of a roll-over pattern-plate support, a vertically reciprocable carrier for said support, means pivotally holding said support to said carrier to rotate relatively to the carrier about a horizontal axis, means for locking the support to the carrier in upright and inverted positions, an upper pressure-resisting head held at a fixed level during mold-forming operations, means for guiding the carrier to move vertically, means adapted to loosely engage the carrier to move the support toward and from a position adjacent the under face of said upper head, a vertically reciprocable mold jarring and squeezing head under the upper head, means for vibrating said vertically reciprocable head up and down with said support seated in upright position thereon, means

for giving said vertically reciprocable head an extended upward mold-squeezing movement while said carrier is in elevated position with the support inverted and subsequently lowering said head independently of the support to withdraw a squeezed mold while the pattern plate is held elevated.

15. In a molding machine, the combination of a roll-over pattern-plate support, a vertically reciprocable carrier for said support, means pivotally holding said support to said carrier to rotate relatively to the carrier about a horizontal axis, means for locking the support to the carrier in upright and inverted positions, an upper pressure-resisting head held at a fixed level during mold-forming operations, means for guiding the carrier to move vertically, means adapted to loosely engage the carrier to move the support toward and from a position adjacent the under face of said upper head, a vertically reciprocable mold jarring and squeezing head under the upper head, means for vibrating said vertically reciprocable head up and down with said support seated in upright position thereon, means for giving said vertically reciprocable head an extended upward mold-squeezing movement while said carrier is in elevated position with the support inverted and subsequently lowering said head independently of the support to withdraw a squeezed mold while the pattern plate is held elevated, and manually-controlled magnetic means carried by the upper head for temporarily holding the support to the head during drawing of a mold.

16. In a molding machine the combination of a base, a mold squeezing means carried by said base, a pattern plate holding head adapted to rest on the mold squeeze means, vertically movable means for supporting the pattern plate holding head independently of the squeezing means, means rotatably supporting the pattern plate holding head to permit it to be rotated about a horizontal axis to invert said head, means for locking the pattern plate holding head in its normal horizontal position and in its inverted position, and an upper pressure head adapted to be engaged by the inverted pattern plate holding head during the mold squeezing operation.

17. In a molding machine the combination of a support, a mold squeezing means carried by said support, a pattern plate holding head adapted to rest on the mold squeezing means, vertically movable means for supporting the pattern plate holding head independently of the squeezing means, means rotatably supporting the pattern plate holding head to permit it to be rotated about a horizontal axis to invert said head, means for raising the pattern plate holding head independently of the squeezing means, means

for holding the pattern plate holding head in elevated position after it has been inverted by rotating it on its horizontal axis, thereby to permit the flask to be lowered 5 away from the pattern plate by the squeezing means, and a conveyor to receive the flask and support it as the squeezing means returns to its normal lower position.

18. In a molding machine, an upper head 10 held in a fixed horizontal plane, a vertically reciprocable mold-squeezing and flask-lowering head, a flask-elevating and inverting head, a pattern plate secured to said last-mentioned head, a vertically shiftable carrier 15 for said flask-elevating and inverting head, means pivotally holding said flask-elevating and inverting head to said carrier to rotate about a horizontal axis, means for raising and lowering said carrier at will, 20 and independently operable means for raising and lowering said mold-squeezing and flask-lowering head while said invertible head is in elevated and inverted position.

19. In a molding machine the combination 25 of a support, a mold squeezing means carried by said support, a pattern plate holding head adapted to rest on the mold squeezing means, a vertical post, a vertically movable sleeve mounted on said post, an air cylinder parallel with the said post, a piston 30 in said cylinder carrying a piston rod rigidly connected to said sleeve, a valve for admitting air to said air cylinder and exhausting it therefrom, means to limit the upward 35 movement of said sleeve, a support rotatable and vertically slidable on said sleeve, a horizontal journal formed on the pattern plate holding head and mounted in a bearing formed in said rotatable and slidable support, an upper pressure head, means for locking 40 the pattern plate holding head in its normal horizontal position and in its inverted position, and means for holding the pattern plate holding head to the upper 45 pressure head after the said head has been inverted by rotating it on its horizontal axis.

20. In a molding machine the combination 50 of a support, a mold squeezing means carried by said support, a pattern plate holding head adapted to rest on the mold squeezing means, a vertical post, a vertically movable sleeve mounted on said post, an air cylinder parallel with the said post, a piston 55 in said cylinder carrying a piston rod rigidly connected to said sleeve, a valve for admitting and exhausting air from said air cylinder, means to limit the upward movement of said sleeve, a support rotatable and vertically slidable on said sleeve, a horizontal journal formed on the pattern plate holding head and mounted in a bearing formed in said rotatable and slidable support, an upper pressure head, means for locking the 60 pattern plate holding head in its normal

horizontal position and in its inverted position, and magnetic means for holding the pattern plate holding head to the upper pressure head after said head has been inverted by rotating it on its horizontal axis. 70

21. In a molding machine the combination 75 of a support, a vertically movable mold squeezing means carried by said support, a pattern plate holding head adapted to rest on the squeezing means, means rotatably supporting the pattern plate holding head to permit it to be rotated about a horizontal axis to invert said head, means for holding the pattern plate holding head in elevated position after it has been inverted by rotating it on its horizontal axis, thereby to permit the flask to be lowered away from the pattern plate by the squeezing means, and means to receive and support the mold flask 80 above the squeezing means as said squeezing means returns to its normal lower position.

22. In a molding machine the combination 85 of a support, a vertically movable mold squeezing means, and means to receive and support the mold flask above the squeezing means as said squeezing means returns to its normal lower position, said flask supporting means being inclined and including antifriction elements adapted to facilitate 90 the lateral removal of the flask from the machine.

23. In a molding machine the combination 95 of a support, a vertically movable mold squeezing means carried by said support, a pattern plate holding head adapted to rest on the squeezing means, means rotatably supporting the pattern plate holding head to permit it to be rotated about a horizontal axis to invert said head, means for holding the pattern plate holding head in elevated 100 position after it has been inverted by rotating it on its horizontal axis, thereby to permit the flask to be lowered away from the pattern plate by the squeezing means, and means to receive and support the mold flask above the squeezing means as said squeezing means returns to its normal lower position, said flask supporting means including antifriction elements adapted to facilitate 105 the lateral removal of the flask from the machine. 110

24. In a molding machine, an elevated squeezing head, means for magnetizing and demagnetizing said elevated head at will, a metallic roll-over head, a pattern plate carried by said roll-over head, means for raising and lowering said roll-over head, a vertically reciprocable lower head, means for jarring said lower head, and means for imparting an extended up and down motion to 120 said lower head. 125

25. In a molding machine, a mold jarring head, a roll-over head having one face adapted to seat on the jarring head, a pattern plate held to the other face of the roll-over 130

- head, a freely vertically slidable carrier for the roll-over head, raising and lowering means adapted to loosely engage said carrier, means for limiting upward movement of the 5 carrier, an upper head, means holding said head at a fixed level over the jarring head slightly above the limit of movement of the roll-over head when inverted, means for rapidly vibrating the jarring head up and 10 down with the roll-over head seated thereon, means for first elevating the jarring head while the roll-over head is in its uppermost inverted position to force said roll-over head upward against the upper head and squeeze 15 a mold suspended from the roll-over head and then lowering the jarring head to normal position, and manually controlled means for holding the inverted roll-over head to the upper head during lowering of the 20 jarring head for drawing a mold downward from the pattern plate and subsequently releasing the roll-over head to permit lowering of said roll-over head upon a downward movement of the carrier elevating and 25 lowering means.
26. In a molding machine, a base, a vertical post held to the base, a horizontally swinging arm held to the upper end of said post, a pressure head suspended from said 30 arm, a jolt and squeeze head supported on the base, means for imparting jolting and squeezing movements to said jolt and squeeze head, fixed means on said base cooperating with said arm to arrest movement of the 35 arm in one direction with said depending head over the jolt and squeeze head, a roll-over head having a pattern-plate supporting face and an opposite face adapted to seat against either said suspended head or said
- jolt and squeeze head, a carrier for the roll-over head freely slidable on said post, vertically reciprocable means mounted on the base adapted to loosely engage under a part of said carrier and move the carrier along the post, and a single horizontal stub-shaft 45 connection between said carrier and the roll-over head.
27. In a molding machine, a base, a vertical post held to the base, a horizontally swinging arm held to the upper end of said post, a pressure head suspended from said arm, a jolt and squeeze head supported on the base, means for imparting jolting and squeezing movements to said jolt and squeeze head, fixed means on said base cooperating with said arm to arrest movement of the arm in one direction with said depending head over the jolt and squeeze head, a roll-over head having a pattern-plate supporting face and an opposite face adapted to seat against either said suspended head or said jolt and squeeze head, a carrier for the roll-over head freely slidable on and rotatable about said post, vertically reciprocable means mounted on the base arranged to loosely engage under 50 a part of the carrier and move the carrier along the post, and a single horizontal stub-shaft connection between said carrier and roll-over head.
28. In a roll-over molding machine, a vertical guide post, a sleeve slidably mounted on the post, a roll-over head having a vertical extension at one side thereof, and a horizontal stub-shaft connection between 55 said sleeve and said extension.

In testimony whereof I hereunto affix my signature.

WILLIAM H. NICHOLLS.
